UNITED STATES PATENT OFFICE

EDWARD J. DOBERSTEIN, OF BLUE ISLAND, ILLINOIS, ASSIGNOR TO GOODMAN MANUFACTURING COMPANY, OF CHICAGO, ILLINOIS, A CORPORATION OF ILLINOIS

MINING MACHINE

Application filed December 29, 1928. Serial No. 683,330.

This invention relates to mining machines and more particularly to mining machines of the overcutting or slabbing type in which a cutting element is mounted for angular movement on a wheeled support. One of the objects of this invention is to provide an improved construction of the cutting element and elevating mechanism. A further object is to provide an improved construction in the operating gearing for feeding the cutter element to the coal.

The invention may be best understood by reference to the accompanying drawings which illustrate one form in which it may be embodied.

In these drawings:

Figure 1 is a side view of a mining machine constructed according to my invention;

Figure 2 is a plan view of the machine drawn to a somewhat larger scale than Figure 1 and with parts broken away to show portions of the mechanism;

Figure 3 is a view in part longitudinal section but showing the cutting element and the elevating devices thereon in full;

Figure 4 is an enlarged sectional view of the cutting element taken on line 4-4 of Figure 2.

Figure 5 is a rear view of the cutting element with parts broken away;

Figure 6 is a transverse section of the cutting element taken on line 6-6 of Figure 2;

Figure 7 is a cross section of the feed gearing taken on line 7-7 of Figure 2;

Figure 8 is a detail view of another portion of the feed gearing taken on line 8-8 of Figure 2.

Referring now to details illustrated in the drawings:

The mining machine comprises a main frame 1 supported on axles 2, 2, having flanged wheels 3, 3 for movement along the mine track in the usual manner. At the forward end of the main frame is a turntable 4 having pivotal bearing on a stud 5 integral with the main frame, as shown in Figure 3. Mounted on the turntable are a plurality of upright supports. As shown herein, these supports comprise a pair of

oppositely disposed frames 6, 6, each having a pair of upright members 7, 7. These frames are preferably connected to the turntable by detachable means, such as bolts 6^a, 6^a. A cutting element 8 is supported between the frames 6, 6 and arranged for vertical adjustment with respect thereto, as will hereinafter appear.

Referring now to details of construction of the cutting element, it will be observed that it comprises an independent unit having as its main elements a cutting arm 9, a main casing 10, and a motor casing 11. The cutter arm 9 is provided with a guide-way 12 for a cutter chain of the usual type (not shown) and is attached to the forward or outer end of the frame 10 and eccentrically thereof, the arrangement being such that the entire cutting element may be inverted when desired so that the cutter arm may be either at the extreme top of the cutting element, as shown in Figure 1, or in inverted position at the bottom of the cutting element and nearer the base frame, as shown in Figure 3. The cutter arm is supported on a bracket 13 formed integral with the main frame. As herein shown the cutter arm is provided with a pair of I-beam sections 15, 15 (see Figure 6), spaced apart to form a longitudinal slot 16 and with a pair of oppositely disposed gibbs 17, 17, secured to the outer flanges of the I-beam members to form the cutter chain slot 12. The lower surface of the bracket 13 is provided with a longitudinally arranged tongue 18, adapted to fit in the slot 16 formed in the cutter arm, and a pair of parallelly arranged projections 19, 19 on the opposite sides of said central tongue, adapted to fit in the recessed portions of the I-beams 15, 15. A pair of straps 20, 20, bear along the lower surfaces of the I-beam members opposite the projections 19, 19, and a plurality of bolts 21, 21, pass through said straps and I-beam members and are threaded in the projections 19, 19, to secure the cutter arm in position. Suitable longitudinal slots 22, 22, as indicated in Figure 4, may be provided in the I-beam sections to afford longi-

90
95
100

tudinal adjustment of the cutter arm respective to the main frame.

The main frame 10 occupies the space between the supporting frames 6, 6, and forms a housing for the gearing mechanism interposed between the motor 11^a and the cutter chain sprocket 25. Said cutter chain sprocket is mounted on a vertically disposed shaft 26 arranged centrally of the main frame, and in line with the cutter arm in position to engage the cutter chain in the usual manner. As shown herein, said sprocket is integral with a hub 27 keyed on said shaft. A beveled gear 28 is carried at the upper end of the shaft and is meshed with a beveled pinion 29 keyed on longitudinal shaft 30. A pinion 31 at the rear end of the latter shaft is meshed with armature pinion 32 of the motor 11^a. As shown herein, a motor 11^a is enclosed in the motor casing 11 at the rear end of the main frame 10, and arranged to be removable from said frame without disturbing the position of the main frame in its support. For this purpose, the main frame 25 is provided with a pair of oppositely disposed wings 34, 34, extending rearwardly on opposite sides of the motor casing 11 and having means thereon for connecting the main frame to the rearmost supporting uprights 7, 7. In the present instance this means comprises the rear pinions 40, 40, forming a portion of the elevating mechanism, which will be hereinafter more fully described. As shown in Figure 5, the motor casing 11 is preferably provided at each side with a pair of oppositely disposed guiding members 35, 35, adapted to engage the wing members 34, 34, and provide a rigid connection therewith, but permitting rearward sliding movement of the motor casing when it is desired to remove the same from the frame. Said casing is detachably connected by suitable means, such as the bolts 36, 36, as shown in Figures 3 and 5. The motor may thus be quickly removed from the cutting element for replacement or repair.

Referring now to details of the elevating mechanism, whereby the cutting element is adjusted vertically of the supporting frames 6, 6, I provide a pair of pinions 40, 40 on a shaft 41 arranged longitudinally of each side of said cutting element, said pinions engaging racks 42, 42 along the inner sides of the uprights 7, 7. Shafts 41, 41 have suitable bearings 44, 44 and 45, 45 in the main frame 10 of the cutting element. Said shafts are each driven at their forward ends by a worm gear 47, 47, each engaging a worm 48 keyed on opposite ends of a transverse shaft 49. The worm gearings 47 and 48 are enclosed in suitable housing, 46. (See Figure 6). Operative connection between the transverse shaft 49 and the motor driven shaft 30 is provided by means of a clutch member 50 feathered on the shaft 49 and engaging a co-op-

erating clutch 51 rotating integrally with a worm gear 52. The latter gear is meshed with a worm 53 keyed on the forward end of the shaft 30.

It will be observed that the bearings 44, 44 and 45, 45, for shafts 41, 41, are split on a vertical plane and detachably secured by bolts 55, 55. (See Figure 5). Similarly, the worm gear housings 46, 46 are split on a vertical plane and detachably secured by the bolts 56, 56. (See Figure 6). By means of this arrangement the entire shafts 41 with their pinions and worm gears may be quickly detached at either side by removing the supporting frame 6 and then removing the bearings 44, 44 and 45, 45, and housing 46.

The elevating mechanism may also be operated by hand from either side of the machine by the application of a crank or similar suitable means to the squared projections 57, 57 on the transverse shaft 49, extending through the housing 46, 46.

The operation of the elevating mechanism will be clear from the description of the above mechanism, it being understood that the clutch member 50 is normally disengaged from the coacting clutch member 51, in which position the elevating mechanism is inoperative and locked against vertical movement by reason of the pitch of the worm gear 47 and the worm 48. Sufficient leverage may be provided by means of a crank, however, to overcome the locking action of these gears when it is desired to operate the elevating mechanism by hand. In order to actuate the mechanism in either direction by means of the motor the clutch member 50 is thrown into engagement with the clutch member 51. The direction of movement of the elevating mechanism is controlled by the direction of rotation of the motor, which is preferably of the usual reversible type.

Referring now to the novel feeding and driving mechanism at the rear end of the machine, illustrated especially in Figures 7 and 8, it will be seen that I provide a motor 60, mounted at the rear end of the main frame and provided with an armature pinion 61, engaging a gear 62 on the transverse shaft 63. Said shaft has bearing in a bracket 64 mounted on the main frame adjacent the gear 62, and a bracket 65 at the opposite end of the shaft. Two separate trains of gearing are driven from the shaft 63, one being for feeding the cutter arm to the work through the medium of the turntable 4, which is mounted for angular movement on the main frame, as hereinbefore described. A flexible cable drum is also driven from this gear train. The second train of gearing is for driving the axle 2 and the supporting wheels 3 to propel the machine from place to place.

As shown herein the feed and cable drum gear train comprises a pinion 68 keyed on a

shaft 68 and meshed with a gear 69 loosely mounted on a countershaft 70. This shaft has bearing in the bracket 65 at one end and in a housing 71 at the other end. The gear 69 is keyed on a pinion 72 meshed with a gear 73 keyed on a sleeve 74 loosely mounted on the shaft 63. A pinion 75 is keyed on the opposite end of sleeve 74, and is meshed with a gear 76 on a sleeve 77 loosely mounted on shaft 70. A sliding clutch member 78 having clutch teeth on opposite sides thereof is feathered on shaft 70 for selective engagement with co-acting jaws on pinion 72 or sleeve 77. In Figure 7 the clutch member 78 is shown in the neutral position. The arrangement is such that when thrown to the left it will engage pinion 72. Shaft 70 will then be driven through gears 68, 69 and 72. When the clutch member 78 is thrown in the opposite direction to engage with the sleeve 77, the shaft 70 will be driven at a lower speed through the members 68, 69, 72, 73, 74, 75, 76 and 77. A worm 80 is carried by the shaft 70. This worm engages a worm gear 81, as shown in Figure 8. Said worm gear is secured to a hub 82 loosely mounted on a clutch sleeve 83. An annular collar 84 is spaced from the lower face of the hub 82 but secured to rotate therewith through a plurality of connecting pins 85 arranged at intervals around the periphery thereof. An annular ring 86 is keyed to the clutch sleeve 83 and is secured in frictional engagement between the hub 82 and the collar 84. A frictional driving connection is thus provided between the clutch sleeve 83 and the two members 82 and 84, by means of tension on the pins 85 maintaining a frictional contact by said members on opposite sides of the ring 86. As shown herein, a pair of bearing rings 87, 87 may be interposed between the friction members to take up wear.

The clutch collar 83 is loosely mounted on a vertically disposed shaft 90. A longitudinally movable clutch member 91 is also mounted on said shaft below the clutch sleeve 83 and is provided with a plurality of clutch segments 92, 92, extending upwardly through apertures 93, 93, formed in the clutch sleeve 83. Clutch sleeve 83 and clutch member 91 therefore rotate together at all times. The upper ends of the clutch segments 92, 92, are adapted to engage clutch jaws 95 carried in a sleeve 96 keyed on the upper end of the shaft 90. A pinion 101 is keyed at the lower end of shaft 90 and is meshed with a gear 102 on the stud 103. A gear pinion 104 is mounted to rotate with the gear 102 and drives a toothed rack 105 formed about the periphery of the turntable 4.

By means of the gearing just described, the turntable with its cutting element may be fed to the coal by swinging the same angularly on the base 1. This angular movement may be made at two speeds by reason of the selective

gearing included in the train as described. By reason of the frictional drive through members 82, 84 and 83, the amount of effective power delivered to feed the cutter arm may be limited so that in case unusually hard cutting is encountered, the friction clutch will slip, and thus protect the parts from damage or danger of breakage. A driving connection is also afforded, to a rope drum 110 which is adapted to receive a draft rope of the usual form. Such rope is for sumping the machine when the latter is moved along the track with the cutter arm locked at a forwardly projecting angle to make the initial cut. It may also be used, if desired, for feeding the cutter arm to the coal to make a slabbing cut with said arm arranged at substantially right angles to cut along one side of the track. The rope drum 110 is loosely mounted on a stud 111 forming a part of the main frame and is provided at its upper surface with a plurality of clutch jaws 112 adapted to be engaged by the clutch member 91 when the latter is moved downwardly.

Means are also provided for affording a positive lock against angular movement of the cutting element. This means comprises an arm 98 (see Figure 2) hinged to the gear casing 99 and adapted to fit in a slot 100 formed at the upper end of the sleeve 93. Since the latter sleeve is keyed on the drive shaft 90, the gearing beyond this point may be locked, including the turntable 4, which is driven thereby. In the arrangement shown, it will be observed that the friction device, comprising the members 82, 84 and 83, is interposed between this locking mechanism and the motor, so that in case it is attempted inadvertently to drive the shaft 90 when it is locked, the friction clutch will slip, and thus protect the parts from breakage. When the arm 98 is raised from the slot 100 the sleeve 93 and the shaft are free to rotate and drive the gearing associated with the turntable for feeding the cutter arm in the usual manner.

The train of gearing for driving the axles and wheels comprises a clutch sleeve 113 loosely mounted on the shaft 63, having clutch jaws 116, 116 adapted for engagement with clutch jaws 115, 115 of the sliding clutch member 114, the latter being feathered on the shaft 63. A pinion 117 is carried on the sleeve 113 and is meshed with spur gear 118 keyed on one end of the counter shaft 119. This shaft is journaled in the brackets 65 and 65^a. Keyed thereon is a chain sprocket 120 adapted to drive the chain 121, operatively connected with an axle sprocket 122, on the axle 2. A brake drum 123 is also mounted upon the sleeve 113 and is provided with a brake band 124 of the usual type. The arrangement is such that when the clutch 114 is thrown into operative engagement with the sleeve 113, the sleeve and brake drum thereon,

together with the gear 118, shaft 119 and sprocket 120 will be revolved, whereby the machine will be moved through the chain 121, sprocket 122 and supporting wheel 3. The 5 brake band 124 may be tightened or released at will by means of the brake wheel 125, to control the wheels in the usual manner.

Although I have shown and described one 10 form in which my invention may be embodied, it will be understood that the construction and arrangement of the various parts may be altered without departing from the spirit and scope of my invention. I do not wish, therefore, to be understood as limiting myself to the specific construction illustrated, except as particularly limited in the appended claims.

I claim as my invention:

1. In a mining machine, a base, a turntable on said base, a cutting element supported for vertical movement on a plurality of uprights spaced apart on said turntable, said cutting element comprising a cutter arm at the forward end of said frame, a motor at 25 the rear end of said frame and detachable connections thereto, permitting rearward withdrawal of said motor and supporting connections mounted on said frame for engagement with said upright supports.
2. In a mining machine, a base, a turntable on said base, a cutting element supported for vertical movement on a plurality of uprights spaced apart on said turntable, said cutting element comprising a frame having a cutter 30 arm projecting from the forward end thereof, said frame having engagement with said upright supports, and a motor detachably connected at the rear end of the frame and extending forwardly and rearwardly of the 35 rearmost supporting connections on said frame.
3. In a mining machine, a base, a turntable on said base, a cutting element supported for vertical movement on a plurality of 40 uprights spaced apart on said turntable, said cutting element comprising a frame having a cutter arm at the forward end thereof, a motor at the rear end of said frame, and detachable connections for said motor comprising 45 a pair of projections integral with said frame and extending on opposite sides of said motor, and supporting connections on said 50 projections adapted for engagement with the rearmost supports on said base.
4. In a mining machine, a base, a cutting element supported for vertical movement on a plurality of uprights spaced apart on said 55 base, said cutting element comprising a frame, a cutter arm at the forward end thereof, pinions on each side of said frame adapted for 60 engagement with vertically disposed racks on said uprights for elevating said cutting element with respect to the base, and a motor at the rear end of said frame having intermediate 65 operative connections selectively with

said cutting element or said elevating pinions.

5. In a mining machine, a base, a cutting element supported for vertical movement on a plurality of uprights spaced apart on said base, said cutting element comprising a frame, a cutter arm at the forward end thereof, pinions on each side of said frame adapted for engagement with vertically disposed racks on said uprights for elevating said cutting element with respect to the base, 70 and a motor at the rear end of said frame having intermediate operative connections selectively with said cutting element and with said elevating pinions, said motor extending forwardly and rearwardly of the 75 rearmost elevating pinions.

6. In a mining machine, a base, a cutting element supported for vertical movement on a plurality of uprights spaced apart on said base, said cutting element being provided 80 with elevating mechanism comprising a pair of elevating shafts on opposite sides of said cutting element, pinions on said shafts engaging vertically disposed racks on the upright supports, and bearing means for said 85 shafts split on a vertical plane and detachable laterally therefrom.

7. In a mining machine, a base, a cutting element supported for vertical movement on a plurality of uprights spaced apart on said base, said cutting element comprising a frame, a cutter arm having a pair of spaced longitudinal channel beams adapted to register with longitudinally disposed bearing surfaces on the front end of said frame including a centrally disposed projection fitting between said beams, other projections fitting in said channel beams, and securing means for said cutter arm comprising a pair of longitudinally arranged plates bearing on the outer surfaces of said channel members, and bolts passing through said plates and channel members and secured in said frame. 100

8. In a mining machine, a base, a cutting element supported for vertical movement on a plurality of uprights spaced apart on said base, said cutting element comprising a frame, a cutter arm having a pair of spaced longitudinal channel beams adapted to register with longitudinally disposed bearing 110 surfaces on the front end of said frame including a centrally disposed projection fitting between said beams, other projections fitting in said channel beams, and securing means for said cutter arm comprising a pair of longitudinally arranged plates bearing on the outer surfaces of said channel members, and bolts passing through said plates and channel members and threaded in said frame, said channel members being provided 115 with longitudinally disposed slots for adjustment of said cutter arm.

9. In a mining machine, a base provided with supporting axles and wheels, a cutting element supported on said base, means for 120

- moving said cutting element angularly with respect to said base to feed the same, other feeding means comprising flexible draft means including a rotating drum therefor, a motor on said base, means operable selectively to feed the cutter arm angularly on said base or to rotate said drum, said means including a friction device interposed between said selective means and said motor, and locking means interposed between said selective means and said angular feeding mechanism whereby the cutting element may be positively locked against angular movement with respect to said base.
- 10 10. In a mining machine, a base, a turntable on said base, a cutting element supported on a plurality of uprights spaced apart on said turntable, said cutting element comprising a frame, a motor detachably connected to the rear end of said frame and permitting rearward withdrawal therefrom, and a cutter arm extending at the front end of said frame and offset vertically from the longitudinal axis thereof, said cutter arm having operative connections with said motor, said cutting element being bodily invertible in said uprights to cut in different horizontal planes.
- 15 11. In a mining machine, a base, a turntable on said base, a cutting element supported for vertical movement on a plurality of uprights spaced apart on said turntable, said cutting element comprising a frame, a motor detachably connected to the rear end of said frame and permitting rearward withdrawal therefrom, and a cutter arm extending at the front end of said frame and offset vertically from the longitudinal axis thereof, said cutter arm having operative connections with said motor, said cutting element being bodily invertible in said uprights to cut in different horizontal planes.
- 20 25 30 35 40 45

Signed at Chicago, in the county of Cook and State of Illinois, this 27th day of December, A. D. 1923.

EDWARD J. DOBERSTEIN.
